UNITED STATES PATENT OFFICE.

HENRY T. PAISTE, OF PHILADELPHIA, PENNSYLVANIA.

FUSE-PLUG.

No. 809,837.

Specification of Letters Patent.

Patented Jan. 9, 1906

Application filed November 23, 1904. Serial No. 234,029.

To all whom it may concern:

Be it known that I, HENRY T. PAISTE, a citizen of the United States, residing in Philadelphia, Pennsylvania, have invented certain 5 Improvements in Fuse-Plugs, of which the following is a specification.

My invention relates to that type of fuse-plug especially designed to receive a cartridge-fuse, the object of the invention being 10 to provide a relatively simple and inexpensive device of the general character above noted which may be screwed into a cut-out of the ordinary construction and whose parts shall be conveniently accessible if it is desired 15 to inspect or replace a fuse. These objects I attain as hereinafter set forth, reference being had to the accompanying drawings, in which—

Figure 1 is a sectional elevation of my improved fuse-plug, particularly illustrating its detail construction. Fig. 2 is a sectional elevation of my improved plug, taken in a plane at right angles to the plane of Fig. 1. Fig. 3 is a sectional perspective view further illustrating the disposition of the various parts of the plug, and Fig. 4 is a modified form of one portion of my improved fuse-plug.

In the above drawings, A is a metallic shell open at one end and closed at the opposite 20 end by a block or head B, of porcelain or other insulating material. Said head is held in position by the turned-over edge of the shell A, which is threaded and is preferably, though not necessarily, provided with an insulating-lining C, usually of fiber. It will be 25 seen that the porcelain piece B is of substantially the form of a truncated cone and has on its end of smaller diameter a metallic plate b in electrical connection with a second 30 metallic plate b' within the shell A. In the preferred construction of my device this second plate or an equivalent structure holds in position a pair of spring-clips b², whose adjacent faces are made concave and whose upper 35 edges are flanged outwardly to a slight extent. Small bolts or rivets a hold the insulating-lining C to the threaded shell A, in addition forming electrical connection between said shell and a second pair of metallic 40 spring-clips D, which project beyond the open end of the shell A and, like the spring-clips b², have their adjacent faces concave in form and their upper edges flanged outwardly.

E is an insulating-tube forming the case of a cartridge-fuse, which, is of the well-known cy-

lindrical form and provided with metallic caps or end portions e, which fit upon the body formed by the insulating-tube E. It will be seen that one pair of spring-clips, as b², is placed to receive and engage one of the metallic ends of the fuse-case, while the second pair, which, as noted, preferably project outside of the threaded shell, is arranged to receive the second metallic end of the fuse-case. 65

A cap or cover-piece, of porcelain or other insulating material F, has its interior threaded, so that it may be screwed over that end of the fuse-plug which has the outwardly-projecting clips D, the opposite end of said 70 plug being adapted to be screwed into a cut-out. In order to most satisfactorily retain the fuse-case in position, I preferably so place the spring-clips b² and D that one set of them engage the said case at points upon the 75 surface of one cap e substantially ninety degrees from the points at which the other cap is engaged by the second set of clips. If desired, the cover F may be omitted, since it is only used in cases where it is undesirable to 80 have the "live" portions of the plug exposed.

With the above-described arrangement of parts it will be seen that the fuse-case may be most conveniently removed from the open end of the plug without the necessity of unscrewing this latter from the cut-out block in which it is used, it being possible, moreover, to examine the condition of the fuse without even taking it from the plug, since with cartridge-fuses of the ordinary construction the indicator-opening e' will be in plain view when the fuse-case is in operative position in my improved plug. 85 90

If considered advisable, the pair of clips which project outside the shell may be made 95 integral with said shell, as illustrated in Fig. 4 at D'. In any case, however, they are so formed and arranged as to permit of the removal of the fuse-case from the open end of the shell. 100

I claim as my invention—

1. The combination in a fuse-plug of a metallic shell and a plate at one end of the same, together forming the terminals of the plug, spring-clips respectively in permanent electrical connection with said terminals, and a cartridge-fuse having terminals placed to be engaged by said clips, substantially as described. 105

2. The combination in a fuse-plug of a metallic shell having at one end a metallic plate, respectively forming with said shell the ter- 110

minals of the plug, a cartridge-fuse, and clips for said fuse respectively in electrical connection with said plug-terminals, a clip or clips extending beyond the end of the shell, substantially as described.

3. In a fuse-plug the combination of a fuse-carrier, a metallic shell of less length than said carrier, a clip or clips connected to the shell and projecting beyond the same for engaging one terminal of the fuse-carrier, a terminal plate, and a second clip connected thereto for engaging the second terminal of the fuse-carrier, substantially as described.

4. In a fuse-plug the combination of a metallic shell having an insulating-lining and a piece of insulating material permanently closing one of its ends, a plate carried by said closing-piece having connected to it a spring-clip, with a second spring-clip permanently connected to the shell, both of said clips being constructed to have the circuit between them completed through a fuse, substantially as described.

5. The combination in a fuse-plug of a metallic shell and a plate respectively forming the terminals of the plug, two clips respectively connected to said terminals, one of said clips being within the shell and the other outside of the same, with a removable cover fitting on the end of the shell having the outer clip, substantially as described.

6. The combination in a fuse-plug of a threaded shell having a cover of insulating material screwed over one end, a terminal piece at the other end of said plug and spring-clips respectively in permanent electrical connection with the shell and with the terminal piece, substantially as described.

7. The combination of a metallic shell, an end piece therefor of insulating material, a terminal piece carried by said end piece, a metallic clip or clips within the shell in connection with the terminal piece, a second clip or clips connected to the shell and extending beyond the end of the same, and a fuse having terminal pieces shaped to electrically connect with said two clips, substantially as described.

8. The combination of a metallic shell, an end piece of insulating material therefor, a terminal piece carried by said end piece, a metallic clip or clips within the shell in connection with the terminal piece, a second clip or clips connected to the shell and extending beyond the end of the same, and a fuse having terminal pieces shaped to electrically connect with said two clips, the end of the shell having the projecting clip or clips being provided with a removable cover, substantially as described.

9. The combination in a fuse-plug of a

shell, an insulating-lining therefor, a spring-clip, a device for electrically connecting said clip and shell, said device also holding said lining in position, a terminal plate insulated from the shell, and a spring-clip connected to said plate, said two clips being shaped to receive a cartridge-fuse, substantially as described.

10. In a fuse-plug, the combination of a casing having terminals including a terminal plate at one end of said casing adapted to engage the contact-piece of a cut-out, the opposite end of said fuse-plug being open, a cartridge-fuse removable from said open end, and means permanently carried by the casing for forming electrical connection between the terminals of said cartridge-fuse and the terminals of the plug, substantially as described.

11. In a fuse-plug, a metallic shell having an insulated terminal plate at one end adapted to engage a contact-piece in a cut-out, the opposite end of said fuse-plug being open, a cartridge-fuse removable from said open end, and means for forming electrical connection between the terminals of said cartridge-fuse and the shell and terminal plate respectively, with a removable cover independent of said connecting means for closing the open end of said shell, the electrical circuit of the plug being independent of said cover, substantially as described.

12. The combination in a fuse-plug of a supporting-body, a metallic shell and a terminal piece on said body, a cartridge-fuse, and means electrically connected to the shell and to the terminal piece for respectively forming electrical connection with the terminals of the fuse, the fuse having an indicator-opening in a portion of its body beyond the end of the plug when said fuse is in position in the plug, substantially as described.

13. The combination in a fuse-plug of a metallic shell and a terminal piece adapted for engagement with the terminals of a cut-out, a cartridge-fuse, and terminal clips respectively connected to the shell and to the said terminal piece, said clips being constructed to be electrically connected by the cartridge-fuse, said fuse projecting beyond one end of the metallic shell so that its indicator-opening is visible while the fuse is in such position as to complete the circuit between the terminals of the plug, substantially as described.

In testimony whereof I have signed my name to this specification in the presence of two subscribing witnesses.

HENRY T. PAISTE.
